PROCESS FOR THE RECOVERY OF HYDRO-CYANIC ACID

Helmut Beier, Frankfort-on-the-Main, Germany,
assignor to Deutsche Gold und Silber Scheideanstalt, Frankfort-on-the-Main, Germany, a corporation of Germany

No Drawing. Application September 23, 1938,
Serial No. 231,327. In Germany April 11, 1938

4 Claims. (CL 204—103)

The object of the present invention is a process for recovering hydrocyanic acid from thiocyanates, which comprises that aqueous solutions of alkali thiocyanates, as sodium thiocyanate, potassium thiocyanate, ammonium thiocyanate and the like, are subjected to electrolysis, whereby perhaps the following reactions may be allowed to take place: the anodically evolved oxygen or the anodically formed hydrogen peroxide oxidizes the separated thiocyanogen radical, whereby on one hand, hydrocyanic acid is formed, while on the other hand, the free sulfur obtained from the thiocyanogen compounds is converted into sulfate or bisulfate.

The working conditions are to be chosen corresponding to these reactions, that is, in such a way that the oxidation products formed at the anode can react in the best manner possible on the thiocyanate or its conversion products. Moreover, it is practicable to prevent the free cyanogen radical obtained at the anode from polymerizing to pseudothiocyanogen.

In carrying out the electrolysis, the electrolyte is heated to temperatures above room temperature, preferably to boiling temperatures. By measures, such as thorough stirring, working with small electrode intervals, expediently by using several such measures, the process may be influenced favorably in the above named sense. The undesired formation and separation of yellow pseudo thiocyanogen at the anode can be prevented by a suitable thiocyanate concentration of the electrolytes. Advantageously liquors are used which are less than approximately 0.6 normal, e. g. 0.4 to 0.5 normal, in cyanate. In working up ammonium thiocyanate excellent results are obtained in working up liquors which contain approximately 40 to 50 g. ammonium thiocyanate per liter. In working up technical crude liquors it has been found that higher thiocyanate concentrations than those stated above do not in general cause difficulties.

The electrolysis can be carried out by direct current, alternating current, fluctuating direct current, or direct current with superimposed alternating current. The above mentioned measures, such as thorough stirring and working with small electrode intervals have been shown to be expedient especially in using direct current. The electrodes may consist e. g. of platinum, suitably platinum gauze. Cathodes of graphite and anodes of magnetite may be used with special advantage. The process can be carried out with and without diaphragms. In using diaphragms it is recommended that the porosity of the same

be so chosen that they permit a rapid passage of the electrolyte and consequently a good exchange between catholyte and anolyte and that the smallest possible electrode interval be chosen. However, it has proved more advantageous to work in cells without diaphragms. Expediently, cells are used which contain a plurality of electrodes united to an electrode system.

For carrying out the process current densities of approximately 7 to 10 amp./dm.² generally have proved most favorable. In working up liquors which contain in addition to thiocyanates, larger or smaller amounts of thiosulfates or sulfites, as e. g. the thiocyanate liquors resulting in the coke and lignite industries, higher current densities, e. g. those up to 15 amp./dm.² and more can be chosen. The voltage may be e. g. 5 to 10 volts.

The most suitable working conditions can be ascertained by simple preliminary experiments.

On account of the formation of sulfate or bisulfate the solution becomes acid in the electrolysis and the hydrocyanic acid formed is caused to escape from the warm acid solution. For promoting the formation and the separation of the hydrocyanic acid as well as for increasing the conductivity of the solution, it is recommended to acidify the electrolyte at the beginning of the electrolysis. As acidifying agent bisulfate or sulfuric acid may be used advantageously, although obviously other acidic materials are likewise suitable.

In order to keep the electrolyte at the desired thiocyanate concentration, it is expedient to introduce into the process continuously or discontinuously concentrated thiocyanate liquor, e. g. liquors resulting in industry, whose thiocyanate concentration is, for the most part, a multiple of e. g. ten times the concentration desired for the electrolysis, e. g. so that the concentration of thiocyanate in the electrolyte is kept constantly at approximately the same amount, e. g. 0.5 normal.

In case of fresh electrolyte mixtures, it has been found that generally about $\frac{1}{2}$ to 1 hour elapses before the hydrocyanic acid yield reaches its most favorable amount. On this basis, it is recommended to begin the addition of more concentrated fresh electrolytes only about $\frac{1}{2}$ to 1 hour after the beginning of the electrolysis. Since the volume of the electrolyte gradually increases by the addition of fresh thiocyanate liquor, whereby the electrodes dip in deeper and the active electrode surface increases, it is recommended to increase correspondingly the addi-

tion of energy so that the current density is kept as constant as possible.

The invention permits the obtaining of hydrocyanic acid and by-products in practically quantitative yields by a simple and easily carried out process; it offers among other things the advantage of making inexpensive raw materials useful, especially the inexpensive thiocyanate liquors resulting on a large scale, e. g. in the gas industry.

Example 1

An aqueous solution which contains about 0.2 normal potassium thiocyanate is electrolyzed with platinum gauze electrodes at boiling temperature with direct current. The current density is about 9 amp./dm.²; the voltage between the electrodes approximately 8 to 9 volts. The electrolyte is slightly acidified with bisulfate before beginning the electrolysis. Hydrocyanic acid which escapes as a gas, is formed immediately after starting the electrolysis. The escaping hydrocyanic acid can be, e. g. liquefied by cooling or e. g. converted into alkali cyanide by absorption in alkali solutions with cooling. The bisulfate formed in the electrolyte can be obtained by the usual measures, e. g. by evaporating the electrolyte. The yield in hydrocyanic acid and bisulfate, calculated on the thiocyanate used, is practically 100%. Small traces of hydrogen sulfide, which possibly escape with the hydrocyanic acid can be separated by the usual methods, e. g. by washing or absorption of the hydrocyanic acid.

Example 2

In an electrolytic cell, adapted to be heated externally and equipped with a thermometer, a reflux condenser as outlet for the escaping hydrocyanic acid, and with an inlet for the addition of liquor, are 50 liters of a crude thiocyanate liquor with a content of 554.8 g. NH₄CNS/l. This crude liquor is diluted to 1 cubic meter. In the electrolytic cell are 3 graphite cathodes and between every two of these plates an anode of magnetite.

The solution is heated to 98-100° and electrolyzed for 30 minutes with a voltage of 5 to 6 volts and a current density of 15 amp./dm.². After this "running time" the continuous addition of undiluted crude liquor begins, i. e. in such a way

that 100 liters of crude liquor with a content of 55.48 kg. NH₄CNS are added in the course of 5 hours.

5 The hydrocyanic acid evolved is liquefied by a known method. After a total of 6 hours, 81.17 kg. NH₄CNS of the 83.22 kg. NH₄CNS are decomposed and thus 22.57 kg. of liquid hydrocyanic acid are obtained. The residual liquor remaining in the electrolytic vessel contains 115 kg. 10 NH₄HSO₄. This can be used for diluting the thiocyanate crude liquor until the concentration of bisulfate becomes so high that the latter precipitates. The electrolysis is carried out efficiently until all of the thiocyanate is decomposed and the bisulfate is obtained by evaporation of the liquor:

I claim:

1. A process for the production of hydrocyanic acid comprising electrolyzing an acidic aqueous 20 solution of alkali thiocyanate containing less than about 0.6 normal alkali thiocyanate at a current density of approximately 7 to 15 amp./dm.², while heating said solution substantially to its boiling point.

25 2. A process for the production of hydrocyanic acid comprising electrolyzing an aqueous solution of an alkali thiocyanate containing less than about 0.6 normal alkali thiocyanate, while heating said solution to a temperature ranging from 30 substantially above that resulting from the passage of the electric current through the solution to the boiling point of said solution, and while maintaining the reactants in intimate contact.

35 3. A process according to claim 2 wherein intimate contact of the reactants is maintained by thorough stirring.

40 4. A process for the production of hydrocyanic acid comprising electrolyzing an acidic aqueous solution of an alkali thiocyanate containing less than 0.6 normal alkali thiocyanate, while heating said solution to a temperature ranging from substantially above that resulting from the passage of the electric current through the solution 45 to the boiling point of said solution, and while maintaining the reactants in intimate contact.

HELMUT BEIER.

CERTIFICATE OF CORRECTION.

Patent No. 2,260,881.

October 28, 1941.

HELMUT BEIER.

It is hereby certified that error appears in the printed specification of the above numbered patent requiring correction as follows: Page 2, second column, line 41, claim 4, before "0.6" insert the word --about--; and that the said Letters Patent should be read with this correction therein that the same may conform to the record of the case in the Patent Office.

Signed and sealed this 2nd day of December, A. D. 1941.
